Primary Examiner — Cathron Brooks*Assistant Examiner* — Cary M Robinson(74) *Attorney, Agent, or Firm* — Cantor Colburn LLP(57) **CLAIM**

I claim, the ornamental design for a display screen or portion thereof with graphical user interface, as shown and described.

DESCRIPTION

The sole FIGURE is a front view of a display screen or portion thereof with graphical user interface showing my new design.

The outermost broken line illustrates the display screen or portion thereof, and the remaining broken lines illustrate portions of the graphical user interface. None of the broken lines form part of the claimed design.

1 Claim, 1 Drawing Sheet(56)
